US00D799768S

(12) **United States Design Patent** (10) **Patent No.:** **US D799,768 S**
(45) **Date of Patent:** **** Oct. 10, 2017**

(54) **ROLLER FOR SUBSTRATE CLEANING**

(71) Applicant: **EBARA CORPORATION**, Tokyo (JP)

(72) Inventor: **Tomoatsu Ishibashi**, Tokyo (JP)

(73) Assignee: **EBARA CORPORATION**, Tokyo (JP)

(**) Term: **15 Years**

(21) Appl. No.: **29/558,926**

(22) Filed: **Mar. 23, 2016**

(30) **Foreign Application Priority Data**

Sep. 24, 2015 (JP) 2015-021002

(51) **LOC (10) Cl.** **15-05**

(52) **U.S. Cl.**

USPC **D32/25**

(58) **Field of Classification Search**

USPC D7/387, 393; D32/25, 40, 35
CPC B08B 1/04; B08B 3/08; B08B 3/02; B05C
17/0207; D04H 18/04; H01L 21/67046

(57) **CLAIM**

The ornamental design for a roller for substrate cleaning, as shown and described.

DESCRIPTION

FIG. 1 is a first perspective view observed from rear, right and top sides of a roller for substrate cleaning showing my new design;

FIG. 2 is a second perspective view observed from front, left and top sides thereof;

FIG. 3 is a front view thereof, a rear view being a mirror image thereof;

FIG. 4 is a top view thereof, a bottom view being identical thereto;

FIG. 5 is a right side view thereof; and,

FIG. 6 is a left side view thereof.

The broken lines depict environmental subject matter only and form no part of the claimed design.

1 Claim, 5 Drawing Sheets
